UNITED STATES PATENT OFFICE.

JOSEPH G. STADELMAN, OF CHICAGO, ILLINOIS.

BUILDING.

1,261,173.

Specification of Letters Patent.

Patented Apr. 2, 1918.

Application filed March 22, 1916. Serial No. 85,825.

To all whom it may concern:

Be it known that I, JOSEPH G. STADELMAN, a citizen of the United States, residing at Chicago, in the county of Cook and State 5 of Illinois, have invented a certain new and useful Improvement in Buildings, of which the following is a full, clear, concise, and exact description, reference being had to the accompanying drawings, forming a part of 10 this specification.

This invention relates to buildings, more particularly to buildings of the portable and sectional type.

There has been a persistent demand in the 15 art for a building of the sectional type, popularly termed "knocked down construction" of a size sufficient to make a suitable shelter for a number of people, or sufficiently large to serve as a garage, or like purposes.

20 The present invention aims to provide a building which is light but substantial, and which is so constructed that it can easily be erected preferably by one man. Each of the individual sections or parts is made of such 25 a size that it can be readily handled by one man. The parts are of such size and bulk as to be readily transportable in a single light wagon. The construction is such that the building may be readily assembled or disas- 30 sembed with a minimum of work and difficulty, but when in assembled position the building will be substantial.

In the accompanying drawings I have 35 illustrated an embodiment of my invention. It is to be understood that the principles of the invention may appear in buildings of different size and constructed for different purposes, that the dimensions and proportions may be varied at will, and that the 40 particular embodiment illustrated is typical.

Figure 1 is a front elevational view of a building constructed in accordance with my invention;

Fig. 2 is a left side elevation of the same; 45 Fig. 3 is a dissected isometric view of a part of the building;

Fig. 4 is a fragmentary horizontal cross sectional view of the corner of the building taken through the wall plate;

50 Fig. 5 is a similar horizontal section taken above the sill;

Fig. 6 is a vertical cross sectional view of the siding and the sill;

Fig. 7 is a horizontal section of the siding, 55 showing the manner of joining the siding panels to the studding;

Fig. 8 is an isometric view of a detail of the roof construction;

Fig. 9 is an isometric view of a part of the roof truss, the wall plate member, and a 60 part of a siding panel; and

Fig. 10 is a cross section of the wall plate member.

Fig. 11 is a fragmentary view showing the wall plate in section and the manner of se- 65 curing the same to the roof trusses.

The building shown in Figs. 1 and 2 is of rectangular form provided with a hip roof. The front of the building is provided with an entrance which is normally closed by the 70 door 1 and a pair of windows 2 and 3. The front is shown to comprise three panels 4, 5 and 6 in which the door and the two windows are placed, respectively. In each case the frame of the door or window is secured 75 into the siding panel and forms a part of the same. The door and the windows may be provided with suitable rain sheds 7 to prevent leakage of rain in through the cracks around the door or window frame. The 80 panels 4, 5 and 6 are rectangular and the space above the panel and between the roof is closed by a suitable gable portion 8, as will be described later.

The roof is composed of a number of sec- 85 tions comprising the similar intermediate sections 9 and the similar end sections 10.

The sides of the building are constructed of a number of panels, 13, 14, 15 and 16, as shown in Fig. 2. The windows 17 and 18 90 are mounted in the end panels 13 and 16, respectively. It is to be understood that if a building of greater length be desired that this can be obtained very readily by the employment of additional side and roof sec- 95 tions. The front and side panels are all made of a standard size as are the intermediate roof sections. The end sections of the roof are increased in width where it is desired to have projecting eaves portions 100 as is shown in Fig. 2. This, however, is unnecessary and the end roof sections may be made similar to the intermediate sections 9.

The frame of the building is constructed 105 as follows: An end sill member 19 is placed at each end and side sill members 20 are connected to the same at the four corners as is illustrated in Fig. 3. The sill members are constructed of two pieces of timber 110 suitably joined together as by nailing or bolting. The timber 21 is of substantially

- twice the breadth of the timber 22, a rabbet or notch being formed thereby, as may be seen in Figs. 3 and 6, into which the lower rail 23 of the adjacent side panel 24 is laid.
- 5 Suitable bolts such as 25 are then passed through the boards of the panel, through the lower rail 23 and through the timber 21 to hold the parts firmly in the position shown in Fig. 6.
- 10 The studs 26 have their ends notched or cut away at 27 and 28, as shown in Fig. 3 and are spaced apart the width of the side panels. These studs 26 are also notched at the point 29 to receive the similarly notched 15 ends of the middle cross rails 30 of the panel sections. The top rail 31 of each panel section has its end notched to lie in the notch 28 in the top of the stud 26. The bottom rail 23 is similarly formed to coöperate with 20 the cut away or notched portion at the bottom of the stud. The notches 33 which are cut in the ends of the cross rails 31, 30 and 23 are of such length as to overlap half the width of the studding 26 so that the adjacent 25 rails of contiguous sections will just fill up the notches in the studding.

The panels are held to the studding by means of bolts such as 35, see Fig. 7. Each bolt 35 passes through a hole 34 formed 30 centrally of the stud on the line between adjacent panels.

The tops of the studding 26 are joined together by a wall plate member 36 which is built up, as may be seen in Figs. 9 and 10.

35 Fig. 10 shows a modified form of the same. The beam 37 is joined to a wider board or beam 38 by means of a narrower strip 39 which is of substantially the thickness of the siding 24. The wall plate member 36 is placed upon the top of the siding panel with the top of the siding 24 which projects above the top rail 31 of each panel lying in the groove 40 formed between the board 38 and the beam 37. The beam 37, 45 which I may term a rail, is of substantially the same thickness as the top rail 31 of the panel section.

A member 41, similar in all respects to the wall plate member 36 secures the front and 50 rear sections together in a similar manner. The gable sections 8 are then secured to the member 41 to close off the triangular space above the front and rear panel sections.

In Fig. 10 I have shown a modification in 55 which the board or plate 38 is made wide enough to extend down in overlapping relation with respect to the top rail 31 of the adjacent section, so that the plate 38 may be bolted to the top rail 31 of the siding panel 60 as by means of the bolts 56. It is obvious that the wall plate shown in either Fig. 9 or Fig. 10 may be bolted, nailed or otherwise fastened to the top edge of the siding 24. In Fig. 9 I have shown the nail 57 as 65 employed for this purpose.

The wall plate member 36 is notched transversely to the rail 37, the fillers 39 and the plate 38 to receive the roof trusses. The notch comprises a lower narrower portion 42 and an upper wider portion 43.

The roof truss comprises the strut or king post 44, the bottom of which rests upon the tiebeam or stringer 45 and the top of which is secured to the rafters 46 and 47. The end of the king post 44 lies below the top of the 75 rafters 46 and 47 and the rafters are nailed to the side of the king post at the ridge of the truss and to the side of the tiebeams or stringers at the eaves of the truss so as to form a groove between them. The tiebeam 80 45 is notched at 48 (see Fig. 9) so as to co-operate with the notch 42 in the wall plate member 36. The wide part of the notch 43 receives the pairs of rafters 47 as can be seen in Figs. 3 and 9. It is to be understood 85 that instead of employing two rafters 46 and 47 on each side of the truss, a single wide rafter with a suitable groove therein might be provided to perform the same function. The groove which is formed between the 90 rafters 46 and 47 is of a width suitable to receive the rails 49 and 50 of adjacent roof sections.

As shown in Fig. 11 a bolt 58 is passed through the tiebeam 45 and the beam 37 of 95 the wall plate member 36 to secure each roof truss to the wall plate. The beam 37 is counterbored to receive the nut 59 is shown in dotted lines.

As can be seen from the drawing of Fig. 100 8, the sides of the rail 49 are flush with the ends of the roof boards 51 which form the body of the roof section. The front and rear roof sections may be formed with projecting gable portions although this is not strictly 105 necessary. The lowermost board 52 is arranged to project out over the ends of the rails 49 and 50 to form projecting eaves. The roof trusses are joined together by the eaves-boards 53 (see Fig. 3) which also hold 110 the roof sections in place. The eaves-boards 53 may be continued up into the gable as at 54 (see Fig. 1) to form a facing or trimming.

The roof sections are secured to the truss 115 members as by bolting the rails 49, 50 of the roof sections to the rafter members 47 of the roof truss. The rail members 49, 50 are perforated at 60 and 61 respectively and these perforations coincide with the perforations 62 in the rafter members 47 so that the bolt 63 can be passed through the parts to secure them together in place.

The seams formed in between adjacent sections of the roof and the seams formed 125 between adjacent sections of the sides and ends may be covered, if desired, with battens or strips of roofing material, if so desired. Inasmuch as the siding panels may be formed of siding strips having tongue 130

and groove joints, it is not generally necessary to apply batten. It is also apparent that a strip of roofing material may be placed upon the seam formed at the ridge of the 5 roof.

It will be apparent from the above that the house which I have described can be readily put together or taken apart, and when put together is substantial and pleasing in appearance. 10

In setting up the house a number of foundation posts or blocks, such as the blocks 55, shown in Fig. 6, are placed upon the ground and the sill members 19 and 20 are 15 then laid upon the foundation blocks. After the sill members have been joined at the corners the stud members 26 are erected and the siding panels are secured to the sill members. Thereafter the wall plate member is 20 mounted upon the ends of the siding and studding and is suitably secured at the corners. The gable portion 8 and the roof trusses are then put in position and after these are in place the roof sections are 25 mounted upon the trusses to complete the building.

Buildings of this type, as heretofore made, have been found structurally weak for resisting storms and winds due to their 30 disintegral construction and were liable to complete demolition when subjected to severe strains. By the employment of the above described means for securing the sections together, as herein illustrated, I secure 35 the distinct advantage of a unitary or homogeneous construction which offers maximum resistance to any disrupting stresses and which, by binding all of the sections together, distributes throughout the structure, 40 any strains to which one section may be subjected.

I do not intend it to be limited to the details shown or described, except as the same appear in the appended claims.

45 What I claim is:

1. In combination a siding panel comprising a top, a bottom and an intermediate rail, the ends of each of said rails being scarfed or notched, a sill member having a 50 groove to receive said bottom rail, a plurality of studs scarfed or notched to receive the scarfed or notched ends of the rails of the siding panel, said studs overlapping the 55 edges of adjacent panels and bolts passing through said studs and holding the adjacent panels thereto. 60

2. In combination a siding panel comprising a top, a bottom and an intermediate rail, the ends of each of said rails being scarfed or notched, a sill member having a 65 groove to receive said bottom rail, a plurality of studs scarfed or notched to receive the notched ends of the rails of the siding panels, said studs overlapping the 70 edges of adjacent panels, bolts passing through said studs and holding the adjacent panels thereto and a wall plate member having a groove, said groove being adapted to fit over the top of said siding panel. 75

3. In combination a tiebeam, a king post secured centrally of said tiebeam, a pair of rafters secured upon each side of said king post, said rafters being secured to said king post and the end of said tiebeam, and a plurality of roof panels, said roof panels comprising cross rails substantially flush with the ends of the panels, said pairs of rafters being spaced apart to receive the adjacent 80 roof rails of two contiguous roof sections. 85

4. In combination a plurality of independent roof trusses, each of said roof trusses comprising a tiebeam, a king post, a pair of rafters secured on each side of said king post to the ends of said tiebeam, a 90 plurality of roof panels having cross rails, the cross rails of adjacent sections lying in the space between said rafters to hold said roof sections or panels together and an eaves-board for connecting the ends of said roof trusses together. 95

5. In combination, a siding panel comprising a top, a bottom and an intermediate rail, the ends of each of said rails being scarfed or notched, a sill member having a longitudinal groove to receive said bottom rail, a plurality of studs scarfed or notched to overlap the scarfed or notched ends of the rails of the siding panel, means to connect the studs and adjoining panels, 100 said studs lying adjacent the edges of adjoining panels to reinforce the same and to receive said connecting means. 105

In witness whereof, I hereunto subscribe my name this 14th day of March A. D. 1916. JOSEPH G. STADELMAN.
